UNITED STATES PATENT OFFICE.

FRANK S. RECE, OF DALLAS, TEXAS.

DECAPITATOR.

1,349,916.

Specification of Letters Patent. Patented Aug. 17, 1920.

Application filed October 24, 1919. Serial No. 332,983.

To all whom it may concern:

Be it known that I, FRANK S. RECE, a citizen of the United States, residing at Dallas, in the county of Dallas and State of Texas, have invented certain new and useful Improvements in Decapitators, of which the following is a specification.

This invention has for its object the simplification of the construction of the decapitator upon which Letters Patent No. 1,310,294, were granted to me July 15, 1919, whereby the process of manufacture will be expedited and the cost of the same reduced, while at the same time the efficiency of the device will be promoted.

The invention is illustrated in the accompanying drawings, in which—

Figure 1 is a perspective view of a decapitator embodying my present improvements;

Fig. 2 is a vertical section taken in a plane parallel with and between the sides of the stock;

Fig. 3 is a horizontal section on the line 3—3 of Fig. 1;

Fig. 4 is a vertical section on the line 4—4 of Fig. 2;

Fig. 5 is a plan view of the blank from which the stock is formed;

Fig. 6 is a plan view of the cutter;

Fig. 7 is a plan view of the blank for the handle;

Fig. 8 is a detail.

In carrying out the present invention, I form the stock from a blank 1 which, as shown in Fig. 5, consists of two substantially similar leaves 2 and 3 joined through the greater portion of their adjacent side edges by a longitudinal web 4. In one end of each leaf 2 and 3, I form perforations or openings 5 and adjacent the said ends the blank may be scored upon the lines 6 to facilitate the subsequent folding. This scoring, however, is not necessary inasmuch as the fold will be upon a line coincident with the adjacent end of the web 4 and the scoring may be difficult inasmuch as the blank will be formed of sheet metal. Intermediate its ends, each leaf is constructed with an L-shaped or bayonet slot or notch 7 and on the outer edge of the leaf 3, immediately adjacent the said bayonet slot or notch at each side of the same, is a lip 8 which may be folded upon a line coincident with the edge of the leaf and of such width that when the blank is folded to form the stock the said lips will bridge the space between the edges

of the leaves. At the ends of the leaves remote from the openings 5, I provide the longitudinally disposed slots 9 which are so located that their inner ends will be aligned with the adjacent end of the web 4 and in the drawings I have shown additional similar slots 10 spaced inwardly from the slots 9 and in alignment therewith. The purpose of these slots will presently appear, but it may be now stated that the slots 10 may be dispensed with without any loss of efficiency in the completed device. In forming the stock from the blank shown in Fig. 5, the said blank is first folded along the web 4 so that the leaves 2 and 3 will be brought into parallelism and the said leaves are then folded upon the lines 6 so that the portions containing the openings 5 will extend laterally from the respective leaves to form feet 75 or securing flanges 11. The lips 8 are folded so as to bridge the space between the free edges of the leaves, as clearly shown in Fig. 1, the free edges of the lips lying flush with the outer face of the wing 2 and bearing 80 against the front edge of said wing. The upper ends of the leaves are folded outwardly along the lines 12 coincident with the upper ends of the slots 9 so that lateral lips or abutments 13 will be formed. The stock 85 will thus be completed and may be secured upon a base block or other fixed support 14 by inserting screws or similar devices 15 through the perforations or openings 5 as will be readily understood. 90

The cutter consists of a narrow shank or stem 16 of sheet metal having a head 17 at its lower end which head is wider than the shank and has its lower edge 18 disposed obliquely so that a blade designed to make a shear cut will be produced. The width of the blade should be approximately equal to the distance between the web 4 and the lips 8 of the completed stock so that when the parts are assembled the said web and lips 100 will form efficient guides for the blade in the operation of the cutter and, by reference to Fig. 2, it will be noted that the blade is so disposed within the stock that its longer vertical edge will be at the front of the stock 105 whereby the blade, when brought in contact with the neck of the fowl, will aid in holding said neck in proper position within the stock. The upper end of the head or blade 17 presents shoulders 19 which form stops 110 to limit the upward movement of the blade as will presently appear. In assembling the

cutter with the stock, the cutter is inserted with the blade downward through the upper open end of the stock and after the blade has passed below the slots 10, if said slots 5 be employed, a clip plate or stirrup 20 is inserted through the said slots, the ends of the said stirrup or clip projecting through the stock and beyond the side of the same to receive a retaining pin 21. Obviously, the 10 sides of the clip or stirrup 20 serve as guides for the cutter by their engagement with the shank of the same and also serve as a stop to limit the upward movement of the cutter through the contact of the shoulders 19 with the lower edges of the stirrup, as shown in 15 Fig. 2. A second stirrup 22, similar in all respects to the stirrup 20, is inserted through the slots 9 and held therein by a pin 23 which is a duplicate of the pin 21. The 20 shank of the cutter is thus very effectually guided in the movements of the cutter so that all wobbling or lateral movement of the cutter is eliminated. Inasmuch, however, as the bridging lips 8 and the web 4 25 constituting the back of the stock furnish extended guides for the cutter by their engagement with the front and rear edges of the blade the lower clip or stirrup 20 may be omitted and this will be done where a 30 shorter stock is desired. After the cutter has been placed in position within the stock as just described, a coiled spring 24 is fitted over and around the shank with its lower end resting upon the abutment lips 13. The 35 upper end of the shank is then equipped with a handle constructed from a sheet metal blank shown in Fig. 7 and consisting of a central elliptical body 25 having narrow tongues 26 extending from its ends. The 40 tongues 26 are folded under the body 25 upon the lines 27 coincident with the ends of the body and are then folded laterally upon the lines 28 so as to project from the body at right angles to the same and at a 45 distance apart approximately equal to the thickness of the shank. The parallel portions of the tongues are then placed against the opposite sides of the shank at the upper end of the same and fastening screws or 50 rivets 29 are inserted through the openings 30 in the tongues and openings 31 in the upper end of the shank alining with the openings 30 so that the handle will be permanently secured to the shank. The side or 55 arcuate edges of the body 25 may be bent slightly downwardly, as shown most clearly in Fig. 2, so that the presser plate presented by the body will be comfortable to the hand of the operator. It will be readily noted 60 upon reference to the drawings that the spring 24 bears against the under side of the handle and the ends of the tongues 26 are adapted to impinge upon the lips or abutments 13 of the stock when the cutter 65 is lowered so as to limit the downward

movement of the cutter and prevent excessive compression and consequent cramping of the spring 24.

The operation of the device is substantially the same as the operation of the decapitator disclosed in my hereinbefore mentioned patent. The fowl to be beheaded is held in position with its neck in the lower end of the slots 7 and its head against one side of the stock. The cutter is then lowered 75 by pressure exerted upon the handle 25 so that the blade will pass across the openings of the slots 7 and cut across the neck of the fowl quickly and without causing unnecessary pain. Upon release of the presser, the 80 spring 24 will expand and raise the cutter which will be limited in its upward movement by the contact of the shoulders 19 with the retaining and guiding stirrup, as previously stated. By my present construction, a smaller blank may be employed for the stock and the formation of the stock from the blank will be expedited so that the cost of manufacture will be very appreciably reduced without any loss of strength 85 in the finished article or decrease in efficiency of the apparatus. The bridging lips 8 effectually prevent movement of the blade through the front of the stock so that the cutting edge is brought firmly against the 90 neck of the animal in every instance and the front longer vertical edge of the blade should be of such length that it will not leave the upper bridge before it engages the lower bridge. After the parts have been 95 once properly assembled, it is not necessary to remove the handle from the cutter in order to sharpen the blade or make other repairs which may be found necessary. Should it be necessary to remove the cutter 100 from the stock, the guiding and retaining stirrups are withdrawn after which the cutter may be lifted bodily through the top of the stock and, of course, the parts may be reassembled by reversing the steps. The 105 spring is very easily and quickly placed in position upon the cutter and the cutter and spring very quickly brought into proper position relative to the stock. Moreover, by my present construction, I am enabled to 110 produce the finished article from less material than has heretofore been necessary. The handle or presser knob or plate employed in my present construction may be very cheaply and rapidly produced and 115 when in position will present a broad surface for the hand of the operator which will permit him to exert all necessary pressure without any discomfort to himself. The blade need not be made from tool steel 120 but may be formed from the same material as the stock, preferably cheap cold rolled sheet metal, the edge of the blade being case hardened. It is to be understood that while I have illustrated the slots 9 and 10 and 125 130

two guiding stirrups, the lower slots and the stirrup engaged therein may be dispensed with as the single stirrup with the lips 8 will effectually guide the blade especially when the blade is full width. In actual manufacture, only one stirrup will generally be employed as I can then use a shorter and, therefore, lighter and cheaper stock, but if the exigencies of manufacture should necessitate the use of a narrow blade it will be desirable to use both stirrups, in which event the lips 8 may be omitted.

Having thus described the invention, what is claimed as new is:

15 1. In a decapitator, the combination of a stock comprising parallel leaves having outstanding abutments at their upper ends and provided with openings to receive the neck of a fowl to be beheaded, said leaves being joined by a longitudinal web at their back edges and having lips bridging the space between their front edges, a cutter fitted between the leaves of the stock for vertical movement and having its blade guided by 25 said web and said lips, a handle on the upper end of the cutter, and a spring coiled around the cutter between said handle and the abutments at the upper end of the stock.

2. In a decapitator, the combination of a stock having an open top, a cutter mounted in and guided by the stock and extending through the top of the same, a handle on

the upper end of the cutter having depending tongues adapted to impinge against the upper end of the stock and thereby limit the 35 downward movement of the cutter, a spring coiled around the cutter between the top of the stock and the handle on the cutter, and means on the stock for limiting the upward movement of the cutter.

3. In a decapitator, the combination of a stock consisting of parallel leaves, a web joining the back edges of said leaves and lips bridging the front edges thereof, a cutter mounted between the leaves and guided 45 by the leaves, said web and said lips, yieldable means for holding the cutter normally raised, means for depressing the cutter, and means for limiting the movement of the cutter.

4. The herein described blank for a decapitator stock consisting of leaves having their adjacent edges connected by a longitudinal web which terminates short of the opposite ends of the leaves, each of said 55 leaves being provided with an L-shaped slot and each leaf being provided with longitudinally disposed slots near one end, and lips projecting from the outer edge of one of the leaves at the opposite sides of the slot 60 in said leaf.

In testimony whereof I affix my signature.

FRANK S. RECE. [L. S.]
